UNITED STATES PATENT OFFICE.

GEORGE C. RUNGE, OF CHICAGO, ILLINOIS, ASSIGNOR TO E. L. MASURE COMPANY, OF CHICAGO, ILLINOIS, A CORPORATION OF ILLINOIS.

DESIGN FOR TASSEL FRINGE.

Application filed July 21, 1924. Serial No. 10,206. Term of patent 7 years.

To all whom it may concern:

Be it known that I, GEORGE C. RUNGE, a citizen of the United States, residing at Chicago, Cook County, Illinois, have invented a new, original, and ornamental Design for Tassel Fringe, of which the following is a specification, reference being had to the accompanying drawing, forming part thereof.

The figure is a face view of a tassel fringe showing my new design.

I claim:

The ornamental design for tassel fringe as shown.

GEORGE C. RUNGE.
